CAN-SEALING MACHINE

Warren D. Jordan, Waukegan, Ill., assignor to
American Can Company, New York, N. Y., a
corporation of New Jersey

Application January 8, 1941, Serial No. 373,687

3 Claims. (Cl. 226—68)

The present invention relates to a machine or apparatus for sealing or closing irregularly shaped containers under other than normal atmospheric conditions, for example as under a vacuum or inert gas pressure, and has particular reference to a machine for rapidly and economically handling filled cans of such character, to the end that vacuum or if desired inert gas pressure conditions may be imparted to and maintained in the cans.

More specifically, the invention is directed to treating and sealing filled cans as above described, wherein each can is packed with a whole or individual ham. Due to the configuration or shape of such product, the cans are of irregular shape as an economical expedient, so as to conform more or less to the shape of the contained product and, generally speaking, these cans while not of triangular cross section may be described as substantially having the form of a truncated cone when viewed in cross section or end elevation.

Cans of such irregular shape are not adapted to be vacuumized or gassed and then sealed in ordinary vacuumizing machines of the character now generally employed for so treating and sealing cans of the usual cylindrical form, and wherein the upper ends of the cans after vacuumizing are introduced into a seaming head and sealed by means of seaming rolls, as the latter are moved inwardly and traverse a circular path of travel in engagement with the can end and body flanges to interfold and interlock the same, for example in the well known double seam. For this reason it has been difficult to provide a machine wherein cans of irregular shape, such as contemplated by the present invention, may be quickly and economically sealed by commercially practicable machinery and under vacuumizing or gassing conditions.

The present invention contemplates the provision of a commercially practicable and economical machine for such a purpose as has been above described.

Whole hams are packed in irregularly shaped cans which are thereafter provided with the usual end seams, but wherein vacuum conditions do not obtain, and therefore air is not excluded from the interior of the can. For the purpose of thereafter treating the closed cans by a machine constructed in accordance with the present improvements, a small vent hole is provided in the can, and adjacent to said vent hole a drop or pellet of solder is placed so as to enable the can to be subsequently vacuumized or gassed

through such a vent hole by means of the instant machine, and after such vacuumizing or gassing operation the vent hole is sealed by melting and flowing the adjacent pellet of solder prior to removing the cans from the air-free condition or environment.

In certain respects the machine constitutes an improvement which is related to the invention disclosed in United States Patent No. 2,162,768, issued June 20, 1939, to Clifford Titchen and Wilhelm Boehl, for Container sealing machine. Said patent discloses a machine wherein cylindrical cans of short size and constituting small job lots may be passed through the usual vacuum closing machine together with full sized lots of the product contained within normal or full sized cans of greater height. Manually operated solder tipping devices are present in such a machine for closing small vent holes in such smaller or short height cans under vacuumizing or gassing conditions and the usual double seaming operation, which is performed in the machine on the taller or standard lot containers, is also operable so as to effect greater efficiency and economy in the handling and sealing of such containers of varying heights. Small job lot containers are not of sufficient height to be elevated into contact with the sealing rollers, and therefore are unaffected thereby as they pass through the seaming head mechanism after they have been sealed under vacuum conditions by a solder tipping operation.

However, the machine disclosed in the Titchen patent is designed for operating on cylindrical cans only, and such a machine could not be employed to accomplish the present improvements which are specifically designed to operate upon cans of irregular configuration, such for example as are employed in the industry for packing whole or individual hams.

It is therefore an object of the invention to provide a machine or apparatus for vacuumizing or gassing and thereafter sealing, such irregular shaped containers under vacuum or pressure and atmosphere-free conditions, by moving the cans through the machine in a continuous procession for the successive described operations.

A further object is the provision in such a machine of automatic means for successively presenting the cans to the atmosphere-free chamber, and immediately thereafter removing from said chamber and in succession cans which have been vacuumized or gassed and subsequently sealed by a manually operated solder tipping operation. All of these steps are performed rapidly

and in a continuous manner by a novel mechanism which has been designed and assembled for obtaining the above described improvements in machines of this character and for the purposes described.

Numerous other objects and advantages of the invention will be apparent as it is better understood from the following description which, taken in connection with the accompanying drawings, discloses a preferred embodiment thereof.

Referring to the drawings:

Fig. 1 is a top plan view of a machine constituting a preferred embodiment of the invention, portions of the same being broken away or shown in horizontal section for clarity of illustration;

Fig. 2 is an end elevation of the machine, partially cut away and partially in vertical section, looking from the entrance or feed-in end thereof or from the lower end of Fig. 1;

Fig. 3 is a central vertical sectional view through the machine, taken on line 3—3 of Fig. 1;

Fig. 4 is an enlarged vertical sectional view taken on line 4—4 of Fig. 1, and illustrating the solder tipping or sealing operation on a filled can after the latter has been vacuumized;

Fig. 5 is a similar view showing the position of the solder tipping mechanism after the sealing operation has been completed or immediately prior to such an operation;

Fig. 6 is an enlarged detail vertical sectional view illustrating the manner of operating and manipulating the soldering iron, said view being taken on the line 6—6 of Fig. 1;

Fig. 7 is an enlarged detail view in vertical section taken on line 7—7 of Fig. 2, and illustrating a portion of the mechanism for advancing and elevating the cans to be vacuumized and sealed;

Fig. 8 is a detail vertical sectional view showing a portion of the mechanism illustrated at the left hand of Fig. 3 and showing a can to be sealed in elevated position within a radial pocket of the turret or conveyor within the vacuumizing chamber; and

Figs. 9, 10 and 11 are similar views illustrating such a can in different positions and also its relation to the advance of succeeding cans to be vacuumized and sealed.

The containers or cans to be vacuumized and sealed are introduced into the machine, for example by hand, to a longitudinally reciprocating feed slide member, by means of which the cans are successively and progressively advanced to beneath a peripheral pocket of a centrally mounted conveyor or turret disposed for intermittent rotation within a closed vacuum chamber sealed against ingress of outside atmosphere. As each can is so positioned it is elevated into a said pocket of the turret while the latter is at rest, and a succeeding movement of the turret sweeps the can from the lifting pad or plunger into the vacuum chamber where desirable vacuum conditions obtain, and by means of which the air from within the can is exhausted through the small aperture which is subsequently sealed by the solder tipping operation.

The said turret pockets are each open from top to bottom to permit vacuumizing of the cans or the supply of gas under pressure thereto, as well as sealing of said cans, through the upper ends of the pockets, and to permit entrance and subsequent discharge of the cans through the lower ends of the turret pockets.

Since the vacuumizing or gassing operation necessarily is carried out through the relatively

small vent hole in the can, the passage of the latter through the vacuum chamber is for a considerable period and preferably is carried out for nearly a complete rotation of 360 degrees of the turret within the vacuumizing or gassing chamber.

The above described intermittent movement of a turret pocket to sweep an incoming can from the lifter pad or plunger into the vacuum chamber for the initial stage of the vacuumizing or gassing operation, simultaneously sweeps a vacuumized and sealed can from the sealing station directly on to the said lifter pad, at which time the turret momentarily comes to rest to permit such sealed can to be removed from the chamber and turret pocket by the descent of the lifter plunger. This movement re-positions the sealed can to be engaged by the reciprocating feed device, to the end that the next feeding movement of the latter advances the sealed can from directly beneath the turret pocket and from the lifter pad to a suitably disposed discharge conveyor operating beneath the turret and vacuum chamber. This movement of the can feed device simultaneously positions the next succeeding can to be sealed upon the lifter pad in readiness to be elevated into an appropriately positioned pocket of the conveyor turret within the vacuum or sealing chamber.

In the disclosed embodiment of the machine a succession of twelve feeding movements of the turret carries the can completely through or around the vacuumizing or gassing chamber to its original entrance position, and means are provided for exerting a vacuum, or if desired gas pressure, on the vented can during all but one of these intermittent movements, the latter being the simultaneous entrance and discharge movements of cans disposed within adjacent turret pockets.

Means are provided to insure against entrance of air into the turret pockets during rotation within the vacuumizing and sealing chamber, while permitting free and intermittent rotation of the turret with a minimum of friction. Means are further provided for firmly holding the cans in predetermined position within the turret pockets so that they cannot shift relative to their original position during their intermittent travel through the chamber. This also facilitates sealing of the cans, which is the final step performed in the machine immediately prior to the discharge of the cans therefrom.

The machine further comprises conveniently and readily manipulative devices for solder tipping the cans at the final sealing station, after the filled cans have been completely vacuumized or gassed, and the machine also contemplates effective devices for intermittently advancing the cans through a longitudinal path of travel relative to the vacuumizing chamber and conveyor turret. These latter means are associated and cooperate with the automatically operative means for intermittently introducing the cans to be sealed into successive turret pockets, as well as removing vacuumized and sealed cans therefrom, and discharging the same from the machine.

A preferred form of apparatus which is disclosed in the drawings, and in which an embodiment of the invention is illustrated, comprises a central base frame or housing generally indicated at 10 and which is of suitable configuration to accommodate and support the various operative parts of the machine. As best seen in Figs. 2 and 3, the said frame portion includes a

substantially centrally and vertically disposed pedestal 11, which serves in part to support a substantially continuous stationary vacuumizing or gassing chamber housing indicated at 12. The latter includes a top plate member 13, a continuous peripheral side wall member 14, and an inwardly extending bottom wall member 15 which may be integrally formed with the said side wall of the chamber and is supported by or constitutes an integral part of the base frame 10.

At its central portion the top plate member 13 of the chamber is provided with a centrally disposed hollow boss portion 16, engaging a reduced portion 17 of the pedestal, and rigidly secured to the latter as by a clamping bolt or nut 18. Said top plate or wall 13 of the vacuum chamber is further formed or provided with a substantially central upstanding wall or housing 19 enclosing or defining an auxiliary chamber 20 adjacent the central supporting medium of the main vacuumizing or gassing chamber 12. This auxiliary chamber is further provided with a central port 21 affording access to a source of vacuum or gas pressure, depending upon the desired use of the machine.

A rotatable conveyor or can receiving turret valve T is disposed within and in close fitting engagement with the chamber 12, and includes a central tubular sleeve member 22 journaled on the pedestal 11, an intermediate closed bottom wall 23, and an outer peripheral wall portion 24 of substantial thickness closely fitting the peripheral side wall 14 of the vacuumizing or gassing chamber 12. Said outer wall of the turret conveyor is cut away from top to bottom at circumferentially spaced intervals to provide open ended, but otherwise closed, can receiving pockets 25 (Figs. 1 and 3), and in the illustrated embodiment of the machine twelve of these pockets are present in the turret or valve, to the end that a said pocket will be positioned at the can receiving and discharge station of the turret at each intermittent rotation of the latter.

The top plate or wall member 13 of the chamber 12 is suitably apertured above all but a single turret pocket for the reception of a nipple 26, and the housing 19 of the auxiliary chamber 20 is similarly apertured at spaced intervals for the reception of a corresponding nipple or tube 27. Suitable radially disposed tubes or conduits 28, which may be constructed of flexible material, serve to connect the said nipples, to the end that communication is afforded between the said auxiliary chamber 20 and each pocket 25 of the turret valve with the exception of the pocket which is disposed at the can entrance and discharge station of the machine. This is for the reason that the turret pocket at said station is in communication with the outside atmosphere, and therefore vacuum or gas pressure conditions at this locality would serve no effective purpose and so are not desirable. The said auxiliary chamber 20 is in communication at its upper end with any suitable air exhausting or vacuum source, or if desired, with a source of inert gas supply, by means of an appropriate pipe connection, a portion of which communicates with said chamber being indicated at 28a.

In the illustrated embodiment of the machine, the bottom wall 23 of the conveyor turret or valve is supported on anti-friction roller bearings indicated at 29 and interposed between the turret valve and an outwardly extended peripheral base portion 30 of the pedestal 11, on which the turret valve is journaled. The central tubular

sleeve portion 22 of the turret valve is suitably bored or apertured at spaced intervals for the reception of compression springs 31 resting at their lower ends against bearing blocks 32 and tensioned at their opposite ends against nut members 33 having threaded engagement with said apertures, and by means of which the tension of said springs which determine the degree of bearing pressure of the valve turret against the bottom wall of a vacuum chamber and against the anti-friction roller bearings 29 may be varied as desired.

The means for intermittently rotating the conveyor or valve turret within the vacuum or pressure chamber 12, comprise a plurality of depending peripherally spaced anti-friction or cam rollers 34, suitably journaled in the bottom wall 23 of the turret, said rollers being disposed and positioned for successive engagement with the spiral groove 35 of a spiral gear element 36 (Figs. 1 and 2) carried by a shaft 37 which may be continuously driven by any appropriate means, not shown, so as to operate in synchronism and in time with other moving parts of the machine.

This Geneva mechanism is a well known mechanical expedient for obtaining intermittent or step-by-step rotation when desired. It will be understood that when a cam roller 34 is engaged by the spiral groove 35 of the continuously rotating spiral gear element 36, the valve turret is rotated for a partial revolution, and during the periods between engagements of said roller and groove, the turret is at rest. The peripheral advance by said groove of a said roller on the turret positions a succeeding roller for subsequent engagement by the spiral groove of the wheel for a further advancement after the rest period.

The filled cans, which may each contain a whole ham and which are to be vacuumized or gassed, and thereafter sealed, are introduced for example by hand at a feeding station generally indicated at A in the drawings. These irregularly shaped cans are indicated at a and are provided with the usual end seams a'. Adjacent one end seam and opposite to the flat side wall of the same, each can is provided with a small vent hole or aperture b and a solder pellet c adjacent thereto. At the feeding station the cans are fed into the machines on their sides and resting upon a flat portion of the side wall as best seen in Fig. 2, with the vent aperture b and adjacent solder pellet c in uppermost position (compare Figs. 1 and 4).

At such station the cans are successively placed upon a flat table 37 adjacent a longitudinally and horizontally reciprocable feed bar or slide member indicated at 38, said cans being positioned between a pair of oppositely disposed upstanding guide elements 39 which, as best seen in Fig. 1, are adjustably mounted to accommodate filled cans of varying dimensions. The said reciprocating feed slide member rests on the table 37 and is retained in position by a gib member 37a secured to the table. The slide member includes a depending lug 40 at its forward end, which extends down through a slot in the table 37 and which serves as a pivotal mounting for a link 42 in turn pivotally secured at its inner end as at 43 to the upper or outer end of a lever 44.

Said lever is secured at its lower end to a rock shaft 45 in turn secured to a bearing member 46 of a suitable web or bracket member 47, in turn secured to or constituting a part of the base frame 10 of the machine. As best seen in Figs.

2 and 7, a rock lever 48 is secured to the shaft 45 and is connected at its upper end to a link or rod 49 in turn connected at its opposite end to a suitable moving part (not shown) of the machine, whereby the shaft 45 and levers 44 and 48 may be rocked or oscillated to reciprocate the feed bar or slide member 38 in time and in synchronism with the other moving parts of the machine.

A lifter pad or plunger 51 is disposed in the path of the slide member 38 so as to receive thereon an incoming can *a* at the conclusion of the inward movement of said slide. The lifter pad is disposed directly beneath a pocket 25 of the turret valve, the bottom wall 15 of the valve casting or vacuum chamber housing being cut away at its forward end as indicated at 52 to provide an entrance opening for the can into the said forwardly positioned turret valve pocket. A pair of stationary guide or wall members 53 are provided on the table 37 on opposite sides of the pad or plunger 51 so as to insure the can will be accurately positioned on the pad directly beneath the entrance opening 52 at the conclusion of the inward stroke of the feed slide bar member 38.

The lifter pad or plunger 51 is carried on the upper end of a rack bar 54 mounted at its opposite ends for vertical sliding movement in a bracket member 55 suitably secured to the machine frame, the latter being apertured as at 56 (Fig. 3) to permit clearance for said rack bar.

A gear sector member 57 is secured to a rock shaft 58 journaled at the upper end of bracket member 47, the teeth of said gear element meshing with corresponding teeth on the vertically reciprocable rack bar 54. A lever 59 is secured to the rock shaft adjacent the gear sector element, and at its lower end is pivotally secured as at 60 to the outer end of a link or rod 61. The inner end of said rod is secured to a suitable operative part of the machine (not shown) in a similar manner as above described in respect to rod member 49 (Fig. 7), so that reciprocation of the rod through gear sector 57 will elevate and lower the lifter pad or plunger 51 in synchronism with the other moving parts of the machine, as will be readily understood.

When a positioned can to be treated and sealed is moved inwardly by the feed bar 38, the lifter pad 51 is in lowermost position, as shown in Fig. 3, so as to receive said can in centered position thereon. The feed bar then moves rearwardly in position to receive thereon a succeeding can, and immediately thereafter the lifter pad is elevated by the described rack and gear mechanism to position its supported can within the open pocket of the turret valve or carrier member, as best seen in Fig. 8, the said turret being momentarily stationary during this movement of the lifter pad. Each pocket 25 of the valve or turret member includes means for yieldingly holding the can in clamped position within its pocket while being treated therein and until it is finally discharged. Such means comprise a clamping element of angular configuration and including a vertical leg 62 mounted for vertical reciprocation within guide members 63 of the turret valve pocket, and a horizontally extending arm 64 having a pad or arm 65 disposed to engage the upper end of a can as the same is projected by the lifter pad into the valve pocket. The said clamping member is normally maintained in a depressed position within its pocket by a tension spring 66 secured at its upper end to the clamping element and suitably secured at its lower end to the turret pocket. The tension of the spring is such as to permit the

clamping element to move upwardly with an incoming can and thereafter the spring tension holds the clamping member against the can during subsequent movements of the turret valve or carrier to accompany the can through or around the machine.

While the can is positioned and held under spring tension within the turret pocket, as shown in Fig. 8, a partial rotation is imparted to the turret valve by the above described movement of spiral gear element 36. This serves to sweep the can from the lifter pad and into the closed non-apertured portion of the turret valve gassing or vacuum chamber 12, as will be understood by reference to Fig. 1 wherein the said intermittent rotation of the turret valve or carrier is in a counter-clockwise direction as indicated by arrow 67.

Assuming the can is to be vacuumized, the described movement of the turret valve carrier positions the can for the first vacuuming operation in a portion of the chamber 12 which is in communication with the first flexible connection 28 at the lower right hand portion of the machine as viewed in Fig. 1, it being understood that such initial vacuumizing chamber is formed by the four walls of the turret pocket or recess 25, and the upper and lower wall members 13 and 15 of the chamber 12. Suction or exhaust is applied at this time to the can through the connections 26, 28, 27, 20, 21 and 28a, and air is exhausted from the can through the small vent hole *b* disposed adjacent a previously applied solder pellet *c*. The succeeding intermittent rotation of the turret valve positions the can for continued vacuumizing through the vent hole beneath the next suction pipe connection 28, as viewed in Fig. 1, and it will be understood that these operations continue during the intermittent rotation of the turret valve, there being a delay for vacuumizing beneath each of the radially extending suction pipe connections 28.

The can sealing station is indicated at *B* and is disposed in the machine immediately adjacent the can entrance and discharge station, and to the left thereof as viewed in Fig. 1. By the time the can reaches the sealing station it has been completely vacuumized through its small vent hole aperture *b* by a series of separate vacuumizing operations at the conclusion of each partial rotation of the turret to place the can beneath the successive radially extending suction pipe connections 28, as best seen in Fig. 1.

The can is now ready for final sealing and during this time it is preferable that the completely vacuumized can remain under vacuum conditions during the sealing operation. Such vacuum at the sealing station *B* is maintained by the final suction pipe connection 28, illustrated at the lower left hand portion of Fig. 1. After the sealing operation the next partial rotation of the turret valve positions the vacuumized and sealed can on the lifter pad plunger 51, which at such time is in elevated position. Such partial rotation of the turret simultaneously moves an incoming can from the lifter pad to the first vacuumizing station, and a sealed can from the sealing station *B* to such elevated lifter pad. This insures that all turret valve pockets of the machine are continuously supplied with cans during operation.

As above described Fig. 8 shows a can to be treated projected into the open chamber of the stationary valve turret with feed bar 38 in re-

tracted position to receive the next incoming can between the adjustable guide members 39.

Fig. 9 shows the lifter pad 51 retracted with a vacuumized and sealed can thereon, and a partial revolution of the turret valve having occurred immediately prior to lowering the lifter pad so as to remove the can in Fig. 8 therefrom for vacuumizing and simultaneously placing the sealed can of Fig. 9 thereon for discharge from the machine.

Fig. 10 illustrates the next operation, wherein the sealed can *a* of Fig. 9 has been further advanced to the right by forward movement of the feed slide member, and onto the endless discharge conveyor. A succeeding can to be sealed is shown at the left in this figure on the lifter plunger in position to be projected into the empty can pocket of Fig. 9. This positioning movement of the left hand can of Fig. 10 is simultaneously with the removal of the sealed can from the lifter pad and while turret valve pocket 25 remains stationary and in the position shown in Fig. 9.

Fig. 11 shows the next succeeding operation, wherein the incoming can at the left of Fig. 10 has been projected by the lifter pad into the stationary can pocket 25 while the feed bar slide member has been retracted for the next can, the first mentioned sealed can being illustrated as further advanced by the endless belt conveyor to final discharge position.

The operation of sealing the vacuumized or gassed cans at sealing station B will now be described, and reference is made to Figs. 1, 2, 4, 5 and 6.

Said sealing station includes an upstanding closed housing 68 suitably secured to the top plate 13 of the valve turret housing 12, and communicating with a valve turret pocket 25 disposed immediately therebeneath by means of a cut away portion or port 69 in said top plate member 13. A shaft 70 is suitably journaled at its opposite ends in side walls 71 of the housing 68 in a manner best illustrated in Fig. 6. One end of the shaft 70 is journaled in a bearing member 72 secured in a suitably apertured portion of one side wall 71, and at its outer end said shaft is provided with a hand operating wheel 73.

The opposite end of the shaft is journaled for rotation within opposed bearing portions 74, 74a, respectively secured to and integrally formed with a partially hollow sleeve member 75, in turn journaled for rotation within a bearing member 76 suitably secured in the opposite side wall 71 of the housing 68. A hand operating wheel 77 is secured to a stud member 78 in turn rigidly secured to the sleeve 75 by means of a transverse pin 79. The shaft 70 intermediate its length is secured as by a pin 80 to the hub portion of a pinion 81 housed within an enlarged portion of the sleeve 75, and having meshing engagement with the teeth of a rack member or bar 82 slidably secured between the bearing member 74 and the inner end of sleeve 75 and disposed in an elongated hollow bracket member 83 formed integrally with the sleeve 75. The said rack bar 82 is further maintained in its described position by a side plate 83a which is secured to the bracket member 83 (see also Figs. 4 and 5). The side plate is formed with a hub portion 84 journaled for oscillatory movement on shaft 70.

Thus the bracket member 83 constitutes a pivotally mounted frame for housing the rack

bar 82 for relative longitudinal movement therein. Said bracket or frame 83 is cut away on its outer face for the reception therethrough of a pair of spaced arms 85 suitably secured to or constituting a part of the rack bar 82 on the portion thereof opposite to the rack teeth. The outer ends of the arms 85 are laterally extended and are of substantially semi-circular configuration so as to receive and be adapted to seat therein the shank portion 36 of an electric soldering iron 87. A pair of split collar members 88 having screws 89 serve to rigidly clamp the soldering iron shank to the spaced arms 85. By loosening the screws the shank of the soldering iron may be adjusted to any desired position longitudinally of its supporting bracket 83 to compensate for cans of varying heights designed to be solder tipped at the sealing station within a positioned pocket 25 of the intermittently rotatable valve turret or carrier.

It will therefore be seen that by the described arrangement the electric soldering iron 87 is designed for longitudinal movement relative to its supporting bracket or frame 83, and is also adapted for oscillating movement bodily with the frame as the latter is rocked on shaft 70. These combined movements permit the desirable and necessary manipulation of the soldering iron for a solder tipping operation on a positioned can as shown in Fig. 4.

Electric power for heating the soldering iron is supplied from any desired source through a hollow conduit 90 having an end thereof suitably secured in the housing 68, a flexible cable 91 (Fig. 4) for carrying the circuit wires to the upper end of the soldering iron and leading from conduit 90, being provided for this purpose. A glass or other transparent panel 92 is seated at 93 against an inclined outer wall portion 94 of the housing 68, said wall portion being apertured as at 95 adjacent the soldering iron, and said transparent panel being removably secured in place in its seat by means of a centrally apertured cover plate or frame 96, in turn secured to said wall portion by means of screws 97 or other securing elements. This affords the solder tipping operator standing exteriorly of the machine a clear view of the solder tipping operation, and enables him to accurately and rapidly manipulate the soldering iron for such purpose. An electric lamp 98 is secured to an appropriate portion of the housing 68 and on the interior thereof, so as to illuminate the interior of said housing, to the end that the operator may readily view the positioned vacuumized or gassed cans to be solder tipped and sealed. Such a lamp may be supplied with power from exteriorly of the machine, as by means of a conduit 99 leading to said lamp, and for example screw threaded into a removable cover plate 100, by means of which said lamp and its socket 101 may be removably secured to the sealing housing 68, as by means of screws 102 or other securing means.

From the foregoing it will be apparent that when a can to be sealed is positioned at sealing station B, for example as viewed in Fig. 5, the soldering iron is in elevated position so as to permit clearance therebeneath of the turret valve pocket 25 as the latter brings a can into position at the sealing station. The operator by rotating handle 73 (Fig. 6) at one end of shaft 70, rotates pinion 81 secured on said shaft and in the proper direction to lower the soldering iron through intermeshing rack bar 82 into the sealing posi-

tion as shown in Fig. 4. Rotation of the opposite hand wheel 77 serves to rotate sleeve 75, which in turn bodily rotates or oscillates the rack bar and its frame housing 83 as a unit about shaft 70 as an axis, and independently of the longitudinal movement of the iron as above described through the hand wheel 73. In this manner the operator can quickly and accurately perform the solder tipping operation while the carrier turret is at rest, and melts the solder so as to fill and seal the vent hole *b* of the now completely vacuumized or gassed can. Upon conclusion of the solder tipping operation, and prior to a further movement or intermittent step-by-step rotation of the can carrying turret valve, the operator again elevates the soldering iron to the position shown in Fig. 5 by turning hand wheel 73 in the opposite direction. This affords the desired clearance to permit a succeeding can to be positioned for sealing.

As has been hereinabove described this positioning of a succeeding can to be solder tipped at the sealing station B simultaneously removes such sealed can from the station and onto the lifter pad 51, which is now in elevated position, as shown in Figs. 8 and 11. The synchronized movements of the mechanism now serve to lower the lifter pad with its sealed can thereon into the position shown in Figs. 9 and 10, where the next succeeding inward can feeding movement of the slide bar 38 removes the sealed can from the pad, and positions it upon the inner end of a suitable discharge conveyor, such as an endless belt conveyor 103, which may be driven from any appropriate and desired power source or moving part of the machine. Such a belt passes over an inner pulley 104 journaled as by a bearing 105 upon an appropriately disposed shaft 106, mounted in opposed wall portions of the base frame 10 in a manner which will be obvious. The outer end of the discharge conveyor passes in a similar manner over a second pulley member (not shown) at the discharge end of the machine, at which point the sealed cans may be removed or discharged to any appropriate place of deposit. The upper can supporting flight of the endless discharge belt conveyor 103 passes over a table element 107 removably positioned in place beneath the said upper belt flight, as by means of inner and outer fixed pin or rod elements 108 secured in the machine frame. Opposite side walls or depending flange portions 109 of the table may be suitably recessed at spaced intervals, as at 110, so as to receive the supporting rod members 108. If desired auxiliary belt supporting antifriction feed rollers 111 (Fig. 3) may be provided to facilitate the discharge of the sealed cans thereon.

The discharge conveyor belt 103 and the cans supported thereon may pass between suitably spaced wall portions 112 of the machine frame, such spaced wall portions constituting a can guiding passageway or tunnel disposed beneath the stationary housing 12 which supports the vacuumizing and can sealing devices.

The invention contemplates but does not disclose means such as an electric motor for operating the various movable elements and devices of the machine, such for example as is clearly disclosed in the patent to Titchen et al. The invention further contemplates the provision in the electrical circuit of appropriately located hand or foot operated switch, within reach of the can sealing operator, to enable the current to be cut off and the machine temporarily stopped if desired when more than the usual time is required

for the solder tipping operation. Such switch means for example are fully disclosed in the aforesaid patent to Titchen et al. However, a skilled operator may perform the solder tipping or sealing operation at sealing station B during the periods when the intermittently rotating can carrying turret or valve is normally at rest, thereby rendering it unnecessary to temporarily cease operation of the machine for this purpose.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

20. 1. In a machine for treating and sealing filled containers, the combination of a substantially closed housing, a peripherally pocketed turret valve mounted within said housing and having means for rotating the same from a container receiving station first through a container treating station and thence to a container sealing station, the peripheral pockets of said valve being open at their bottom ends and successively registrable with an opening in the bottom wall of said housing, means for successively positioning said containers beneath said housing in registry with said housing opening, reciprocating means operable in one direction to project a positioned container to be treated and sealed through said opening into a valve pocket in registry therewith and in the opposite direction to remove through said housing opening a treated sealed container from a succeeding valve pocket to be discharged from the machine, and means for actuating said reciprocating means for the purposes described.
25. 2. In a machine for vacuumizing and sealing filled containers partially open to atmosphere, the combination of a substantially closed stationary housing, a peripherally pocketed turret valve mounted within said housing and having means for rotating the same on a fixed vertical axis from a container receiving station first through a container vacuumizing station and thence to a container sealing station within said housing, the peripheral pockets of said valve being open at their top and bottom ends and successively registrable with an opening in the bottom wall of said housing, independent means at said container vacuumizing and sealing stations respectively for vacuumizing and thereafter for sealing the partially open filled containers, means for successively positioning containers to be vacuumized and sealed beneath said housing in registry with said housing opening, reciprocating means operable in one direction to project a positioned container to be vacuumized and sealed through said opening into a valve pocket in registry, therewith and in the opposite direction to remove through said housing opening a vacuumized sealed container from a succeeding valve pocket to be discharged from the machine, and means for actuating said reciprocating means for the purposes described.
30. 3. In a machine for gassing and solder sealing filled containers partially open to atmosphere, the combination of a substantially closed stationary housing, a peripherally pocketed turret valve mounted within said housing and having means for intermittently rotating the same
35. 4. In a machine for treating and sealing filled containers, the combination of a substantially closed housing, a peripherally pocketed turret valve mounted within said housing and having means for rotating the same from a container receiving station first through a container treating station and thence to a container sealing station, the peripheral pockets of said valve being open at their bottom ends and successively registrable with an opening in the bottom wall of said housing, means for successively positioning said containers beneath said housing in registry with said housing opening, reciprocating means operable in one direction to project a positioned container to be treated and sealed through said opening into a valve pocket in registry therewith and in the opposite direction to remove through said housing opening a treated sealed container from a succeeding valve pocket to be discharged from the machine, and means for actuating said reciprocating means for the purposes described.
40. 5. In a machine for vacuumizing and sealing filled containers partially open to atmosphere, the combination of a substantially closed stationary housing, a peripherally pocketed turret valve mounted within said housing and having means for rotating the same on a fixed vertical axis from a container receiving station first through a container vacuumizing station and thence to a container sealing station within said housing, the peripheral pockets of said valve being open at their top and bottom ends and successively registrable with an opening in the bottom wall of said housing, independent means at said container vacuumizing and sealing stations respectively for vacuumizing and thereafter for sealing the partially open filled containers, means for successively positioning containers to be vacuumized and sealed beneath said housing in registry with said housing opening, reciprocating means operable in one direction to project a positioned container to be vacuumized and sealed through said opening into a valve pocket in registry, therewith and in the opposite direction to remove through said housing opening a vacuumized sealed container from a succeeding valve pocket to be discharged from the machine, and means for actuating said reciprocating means for the purposes described.
45. 6. In a machine for treating and sealing filled containers, the combination of a substantially closed housing, a peripherally pocketed turret valve mounted within said housing and having means for rotating the same from a container receiving station first through a container treating station and thence to a container sealing station within said housing, the peripheral pockets of said valve being open at their top and bottom ends and successively registrable with an opening in the bottom wall of said housing, independent means at said container treating and sealing stations respectively for treating and sealing the partially open filled containers, means for successively positioning containers to be treated and sealed beneath said housing in registry with said housing opening, reciprocating means operable in one direction to project a positioned container to be treated and sealed through said opening into a valve pocket in registry therewith and in the opposite direction to remove through said housing opening a treated sealed container from a succeeding valve pocket to be discharged from the machine, and means for actuating said reciprocating means for the purposes described.
50. 7. In a machine for vacuumizing and sealing filled containers partially open to atmosphere, the combination of a substantially closed stationary housing, a peripherally pocketed turret valve mounted within said housing and having means for rotating the same on a fixed vertical axis from a container receiving station first through a container vacuumizing station and thence to a container sealing station within said housing, the peripheral pockets of said valve being open at their top and bottom ends and successively registrable with an opening in the bottom wall of said housing, independent means at said container vacuumizing and sealing stations respectively for vacuumizing and thereafter for sealing the partially open filled containers, means for successively positioning containers to be vacuumized and sealed beneath said housing in registry with said housing opening, reciprocating means operable in one direction to project a positioned container to be vacuumized and sealed through said opening into a valve pocket in registry, therewith and in the opposite direction to remove through said housing opening a vacuumized sealed container from a succeeding valve pocket to be discharged from the machine, and means for actuating said reciprocating means for the purposes described.
55. 8. In a machine for treating and sealing filled containers, the combination of a substantially closed housing, a peripherally pocketed turret valve mounted within said housing and having means for rotating the same from a container receiving station first through a container treating station and thence to a container sealing station within said housing, the peripheral pockets of said valve being open at their top and bottom ends and successively registrable with an opening in the bottom wall of said housing, independent means at said container treating and sealing stations respectively for treating and sealing the partially open filled containers, means for successively positioning containers to be treated and sealed beneath said housing in registry with said housing opening, reciprocating means operable in one direction to project a positioned container to be treated and sealed through said opening into a valve pocket in registry therewith and in the opposite direction to remove through said housing opening a treated sealed container from a succeeding valve pocket to be discharged from the machine, and means for actuating said reciprocating means for the purposes described.
60. 9. In a machine for vacuumizing and sealing filled containers partially open to atmosphere, the combination of a substantially closed stationary housing, a peripherally pocketed turret valve mounted within said housing and having means for rotating the same on a fixed vertical axis from a container receiving station first through a container vacuumizing station and thence to a container sealing station within said housing, the peripheral pockets of said valve being open at their top and bottom ends and successively registrable with an opening in the bottom wall of said housing, independent means at said container vacuumizing and sealing stations respectively for vacuumizing and thereafter for sealing the partially open filled containers, means for successively positioning containers to be vacuumized and sealed beneath said housing in registry with said housing opening, reciprocating means operable in one direction to project a positioned container to be vacuumized and sealed through said opening into a valve pocket in registry, therewith and in the opposite direction to remove through said housing opening a vacuumized sealed container from a succeeding valve pocket to be discharged from the machine, and means for actuating said reciprocating means for the purposes described.
65. 10. In a machine for gassing and solder sealing filled containers partially open to atmosphere, the combination of a substantially closed stationary housing, a peripherally pocketed turret valve mounted within said housing and having means for intermittently rotating the same
70. 11. In a machine for treating and sealing filled containers, the combination of a substantially closed housing, a peripherally pocketed turret valve mounted within said housing and having means for rotating the same from a container receiving station first through a container treating station and thence to a container sealing station within said housing, the peripheral pockets of said valve being open at their top and bottom ends and successively registrable with an opening in the bottom wall of said housing, independent means at said container treating and sealing stations respectively for treating and sealing the partially open filled containers, means for successively positioning containers to be treated and sealed beneath said housing in registry with said housing opening, reciprocating means operable in one direction to project a positioned container to be treated and sealed through said opening into a valve pocket in registry therewith and in the opposite direction to remove through said housing opening a treated sealed container from a succeeding valve pocket to be discharged from the machine, and means for actuating said reciprocating means for the purposes described.
75. 12. In a machine for vacuumizing and sealing filled containers partially open to atmosphere, the combination of a substantially closed stationary housing, a peripherally pocketed turret valve mounted within said housing and having means for rotating the same on a fixed vertical axis from a container receiving station first through a container vacuumizing station and thence to a container sealing station within said housing, the peripheral pockets of said valve being open at their top and bottom ends and successively registrable with an opening in the bottom wall of said housing, independent means at said container vacuumizing and sealing stations respectively for vacuumizing and thereafter for sealing the partially open filled containers, means for successively positioning containers to be vacuumized and sealed beneath said housing in registry with said housing opening, reciprocating means operable in one direction to project a positioned container to be vacuumized and sealed through said opening into a valve pocket in registry, therewith and in the opposite direction to remove through said housing opening a vacuumized sealed container from a succeeding valve pocket to be discharged from the machine, and means for actuating said reciprocating means for the purposes described.

on a fixed vertical axis from a container receiving station first through a container gassing station and thence to a container sealing station within said housing, the peripheral pockets of said valve being open at their top and bottom ends and successively registrable with an opening in the bottom wall of said housing, independent means at said container gassing and sealing stations respectively for gassing and thereafter for solder tipping the partially open filled containers, means for successively positioning containers to be gassed and sealed beneath said housing in registry with said housing opening,

vertically reciprocable means operable in an upward direction to project a positioned container to be gassed and sealed through said opening into a valve pocket momentarily in registry here-
5 with and in a reverse downward direction to remove through said housing opening a gassed and solder sealed container from a succeeding valve pocket to be discharged from the machine, means for actuating said vertically reciprocating means for the purposes described, and means for discharging the gassed and solder sealed containers from the machine.

WARREN D. JORDAN.
